UNITED STATES PATENT OFFICE.

EMELINE H. BOYDEN, OF PROVIDENCE, RHODE ISLAND.

CLASP FOR TEXTILE GOODS.

SPECIFICATION forming part of Letters Patent No. 535,047, dated March 5, 1895.

Application filed September 7, 1894. Serial No. 522,344. (No model.)

To all whom it may concern:

Be it known that I, EMELINE H. BOYDEN, of Providence, in the county of Providence and State of Rhode Island, have invented certain new and useful Improvements in Clasps for Textile Goods; and I do hereby declare that the following is a full, clear, and exact description thereof, reference being had to the accompanying drawings, and to the letters of reference marked thereon, which form a part of this specification.

This invention relates to that class of clasps used on textile goods, to hold dress shields in place, to attach tickets to goods or samples together, and other analogous uses. Its construction is fully explained and illustrated in the accompanying specification and drawings.

Figure 1, is a top view, enlarged, of the piece of metal that forms the clasp, as it is struck out of a sheet of metal. Fig. 2, represents the same, with the points and legs bent up into position to be used. Fig. 3, shows the clasp as it is when applied to the goods, which are not shown in the drawings. Fig. 4, is a transverse section of the clasp on line x, x , in Fig. 3. Figs. 5 to 7, show the application of the clasp, to hold a dress sleeve shield in place, when in use. Figs. 8 and 9, show the application of the clasp, to hold a dress neck shield in place in a dress. Figs. 10 and 11, show the appearance of the shield on both sides of the goods, when used to hold two or more samples together.

The construction of the clasp is as follows: A piece of metal is struck out of a sheet, by means of a punch and die, in the shape shown in Fig. 1, with a disk A, which may be round or of some other outline if preferred, and having two tapering legs e, e , extending out on one side parallel to each other. A cut is then made with a sharp punch through the metal in the center of the disk, in the shape of a letter N, forming two sharp points h, h , which are bent up at right angles to the disk, as in Fig. 2. A slot or recess g , is made in each leg lengthwise in a line with the base of the corresponding point h , on the disk, so that when the legs e , are bent over as in Fig. 3,

the points h, h , will enter the recesses g, g , in the legs. When the clasp is ready for use, 50 the legs are not bent over farther than shown in Fig. 2.

In Figs. 5 to 7, the line c , represents the dress, line i , the lower side of the sleeve, the two being stitched together at the armhole at r . 55 In Fig. 6, the same parts c, i , are shown, with the ordinary sleeve shield represented by the line a, a , folded over the parts c, i , in the usual way, and in Fig. 7, the clasp A, is shown as applied to the shield a , which is done by 60 passing it down over the fold and pressing the disk and legs e , together until the points h, h , penetrate through the goods and enter the recesses g , in the legs e, e , the points of the legs e , being curved in slightly, so as to 65 enter the shield sufficiently to prevent their catching in anything.

In Figs. 8 and 9, the application of the clasp to the neck part of the dress to hold a shield there, is shown. The lines s , represent the neck band of the dress, made by folding a strip over and stitching the edges together at r' , with the edge of the dress d , between them. The legs e , of the clasp are passed up between the dress d , and the inner 75 fold of the neck band, between the stitches that hold them together. The shield f , held in position of the dotted lines f' , in Fig. 9, has its edge inserted between the disk of the clasp and the inside of the neck band s . The 80 clasp is then pressed together, and the points h , pass through the shield f , and the inner part of the neck band s , and the shield is then turned down as represented by the full line f , Fig. 9. In this application, both the legs 85 and disk of the clasp, are covered from view.

Figs. 10 and 11, represent the clasp holding two or more samples of goods a' , together; the two views representing the different sides of the goods and clasp. Figs. 5 to 10, are 90 shown in section, and from Figs. 5 to 11, the shield where it is shown, is represented at about the size it is used for most purposes, though its size would be governed by the purpose it is to be used for.

Having thus described my improvements,

I claim as my invention and desire to secure
by Letters Patent—

As an article of manufacture, a clasp for
use on textile goods, consisting of a disk hav-
5 ing points raised on its surface, and two ta-
pering legs parallel with each other, on one
side, said legs having slits or recesses made
lengthwise in them and in position to receive

the points on the disk, when said disk and
legs are folded together, substantially as de-
scribed.

EMELINE H. BOYDEN.
